UNITED STATES PATENT OFFICE.

FRANK E. MULLIN, OF PENNANT, SASKATCHEWAN, CANADA.

WIRING CONNECTION FOR AUTOMOBILE-LIGHTS.

1,295,191.

Specification of Letters Patent.

Patented Feb. 25, 1919.

Application filed June 2, 1917. Serial No. 172,475.

To all whom it may concern:

Be it known that I, FRANK E. MULLIN, a subject of the King of England, residing at Pennant, in the Province of Saskatchewan and Dominion of Canada, have invented a new and useful Wiring Connection for Automobile-Lights, of which the following is a specification.

The present invention relates to wiring connections for use in systems of wiring for automobile lamps and for other purposes.

The main object of the invention is the provision of means for connecting a number of binding posts or other terminals to a conductor.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

The figure is a view in elevation of the device.

In the drawing the connection or bus bar 30 is shown formed of wire doubled longitudinally and having spaced twisted portions with loops 7 therebetween and at the ends, one end loop 7 having an extension or eye 8 for the connection of a conductor, not 35 shown. The loops 7 are adapted to be slipped over binding posts or like terminals so that such terminals may be readily connected to the conductor.

Having thus described the invention, what 40 is claimed is:—

A bus bar embodying a doubled wire having spaced loops to fit on binding posts, and twisted portions between said loops, the wire having an extended eye at one end of 45 the bar for the attachment of a conductor.

In testimony that I claim the foregoing as my own, I have hereto affixed my signature in the presence of two witnesses.

FRANK E. MULLIN.
